UNITED STATES PATENT OFFICE

EDWARD A. EVERETT, OF DETROIT, MICHIGAN, ASSIGNOR TO THE UNION
SWITCH AND SIGNAL COMPANY, OF SWISSVALE, PENNSYLVANIA, A
CORPORATION OF PENNSYLVANIA.

TRAIN-ANNUNCIATOR.

No. 835,605.

Specification of Letters Patent.

Patented Nov. 13, 1906.

Application filed May 8, 1906. Serial No. 315,750.

To all whom it may concern:

Be it known that I, EDWARD A. EVERETT, a citizen of the United States, residing at Detroit, in the county of Wayne and State of Michigan, have invented certain new and useful Improvements in Train-Annunciators, of which the following is a specification.

My invention relates to train-annunciators, and has more particular reference to that class of annunciator used for indicating the approach or presence of cars or vehicles at a particular point or on a defined section of track.

I will describe a train-annunciator embodying my invention and then point out the novel features thereof in claims.

In the accompanying drawings, Figure 1 is a side elevation of a train-annunciator embodying my invention, the casing or cover for the same being shown in section. Fig. 2 is a sectional elevation thereof, taken on the irregular dotted lines 2 2 of Fig. 1. Fig. 3 is a view similar to Fig. 1, showing the operating parts in another position. These views illustrate my invention as constructed and arranged for use with a normally open circuit. Fig. 4 is a view similar to Fig. 3, illustrating my invention as constructed and arranged for use with a normally closed circuit.

Similar reference characters designate corresponding parts in all the figures of the drawings.

Referring to the drawings, A designates a suitable casing having a cover B, the latter being provided with an opening C, before which is exposed to view a display device D, formed of a card or other device for displaying information. There may be a plurality of openings and a plurality of display devices, each display device being operated from an independent mechanism. The card or device D has two positions, in one of which the presence of a train or vehicle at any part or in any defined section of track is denoted.

E designates electromagnets, and e an armature. The electromagnets E may be included in an open circuit or in a closed circuit, as the requirements of the railway may demand. In both arrangements the operation of the annunciator is practically the same—that is, the energizing of the electromagnet in one instance will serve to effect the release of the card or device D to permit

it to drop and give proper indication, while the deenergizing of the electromagnets in the other instance will accomplish the same end.

Referring to Figs. 1, 3, and 4, it will be noted that the card or device D is arranged on the free end of an arm D', which latter is pivotally supported in bearings F, arranged in the casing B, its opposite end being provided with a plurality of arms or extensions d d' d''. The arm or extension d is preferably provided with a projection which engages a shoulder s, located at the free end of a latch or pawl f, and when the projection engages the shoulder the pawl f holds the card or device D in its lifted or normal position. (Shown in Figs. 1 and 4.)

g designates a pawl suspended from the armature e. The latch or pawl f rests upon the arm or extension d, and its extremity normally engages a tooth or shoulder g', provided on the pawl g (in the construction illustrated in Figs. 1, 2, and 3) when the armature e is not attracted by the electromagnets E.

When the parts are in the position shown in Fig. 1, it will be evident that when the electromagnets E are energized by the action of a train at a determined point or in a defined section of track the armature e will be lifted, and with it the pawl g, thereby disengaging the pawl f from the arm or extension d. This action releases the card or device D and permits it to drop to the position shown in Fig. 3, thus denoting the position of the car or train. The arms or extensions d' and d'' are adapted to engage a projection d³, which acts as a stop to limit the movement of the card or device D in either direction, and the extension d² may, furthermore, be employed to engage contact-plates p p', which connect, respectively, with the negative and positive wires p² p³ in a local circuit leading to a suitable audible or visual signal X, (see Fig. 2,) arranged near the annunciator and in a tower or terminal located at a distance from the block-section with which the annunciator is in electrical circuit.

In the construction illustrated in Fig. 4, which, as before mentioned, is operable with a closed circuit leading from the electromagnets, the latch or pawl f has connected to it at its free end a finger f', which projects beyond the extremity of the latch or pawl f and

which is adapted to be engaged by a tooth or shoulder g^2 on the pawl g as the latter falls with the armature e when the electromagnets E are deenergized, the arrangement being such that the latch or pawl f by this movement will be lifted out of engagement with the arm or extension d and the card or device D allowed to fall.

- As will be noted, the finger f' is here shown as being pivotally connected to the latch or pawl f , and both are arranged to rest upon the upper end of the arm or extension d , so that when the tooth or shoulder g^2 in its downward movement engages the finger f' it will 10 depress the latter, and with the nose on the extension d , acting as a fulcrum, the latch or pawl f will be lifted so as to release the card or device D , permitting it to fall to the position shown in Fig. 3, thereby effecting the 15 closing of the local bell-circuit and disclosing before the opening or window C the characters or words, as previously described. In both instances and while the parts are in this position the audible signal is sounded 20 and under ordinary circumstances, and especially in the construction of annunciators at present in use, would continue to sound so long as a train or vehicle remained at a certain point or in the defined section of track. 25 To prevent this and overcome what has been considered among railway operators as an annoyance and to provide means whereby the audible signal may be stopped, is an object of the present invention.
- 30 H designates a rod which at one end is connected to the arm D' , its other end extending through the casing B , where it may terminate in an eye h or be provided with any other suitable handle to be grasped by the operator in restoring the display device to its normal position. The connection between this rod and the arm D' being on the opposite side of the pivotal support to that on which the card or device D is carried, it follows that when the annunciator is in the 35 position shown in Fig. 3 a pull upon the rod h will lift the outer end of the arm D' until the nose on the end of the arm or extension d passes beyond the shoulder s on the latch or pawl f , and the extension d will also be withdrawn from engagement with the contact plates $p p'$, thereby breaking the local circuit of the audible signal.

The pawls f and g engage each other after 5 the pawl f has been lifted out of engagement with the arm or extension d ; but when the latter engages the lower extremity of the pawl g during the downward movement of the arm D' it will force the pawl g outwardly, so as to 10 disengage it from the end of the latch or pawl f , thereby permitting the latter to fall and rest upon the upper edge of the extension d , ready to engage the projection thereon when the arm D' is restored to its normal position, as clearly shown in Fig. 3.

If through any abnormal conditions the armature e should be actuated after the arm D' has been restored to its normal position by being momentarily released from the electromagnets E , the latch or pawl f will of course be lifted by reason of shoulder g^2 passing under it, and the arm D' will thereupon fall, closing the local bell-circuit and sounding the alarm. Should a like occurrence take place in the construction shown in Fig. 4, the tooth g^2 will move the finger f' and likewise cause the release of the card device D . A pull upon the handle h will, however, readily restore the parts to their former position.

It will be noted that the lower extremity of the pawl g is preferably formed with a nose or projection g^3 , which normally rests in close proximity to the arm or extension d in order that it may the more quickly contact with and disengage the pawl g from its engagement with the latch or pawl f after the latter has been lifted to release the arm D' .

Having thus described my invention, what I claim, and desire to secure by Letters Patent, is as follows:

1. An annunciator having in combination a display device, a pawl for holding it in one position, an electromagnet and coacting armature, a pawl operated by the armature and adapted to engage the first pawl whereby when said armature is operated the first pawl is moved to release the display device, and audible signal operated by the display device when in its released position, and means for stopping the audible signal and returning the display device to the first position, while the armature is attracted.

2. An annunciator having in combination a display device, a pawl for holding it in one position, a second pawl adapted to engage the first pawl, an electromagnet and coacting armature to which the second pawl is connected and whereby, when said armature is moved, the first pawl is made to release the display device, an audible signal operated by the display device when released, and means for stopping the audible signal and returning the display device to the first position without a movement of the armature.

3. An annunciator having in combination a display device, a pawl for holding it in one position, a second pawl, an electromagnet and coacting armature to which the second pawl is connected and whereby, when said armature is moved the first pawl is made to release the display device, a circuit including an audible signal close by the display device in its released position, and means for opening the said circuit, and returning the display device to the first position, without a movement of the armature.

4. An annunciator for railway signaling purposes having in combination a display device, means for holding the display device in one position, an electromagnet and armature

for releasing the display device, an audible signal, operated when the display device is in its released position, and means for stopping the audible signal and returning the display device to the first position without affecting the electromagnet or its armature.

5 In testimony whereof I have signed my

name to this specification in the presence of two subscribed witnesses.

EDWARD A. EVERETT.
